UNITED STATES PATENT OFFICE.

WILLIAM H. BRISTOL, OF WATERBURY, CONNECTICUT, ASSIGNOR TO THE BRISTOL COMPANY, OF WATERBURY, CONNECTICUT, A CORPORATION OF CONNECTICUT.

ELECTRICAL INDICATING OR RECORDING APPARATUS.

1,059,328.

Specification of Letters Patent.

Patented Apr. 15, 1913.

Application filed March 30, 1912. Serial No. 687,450.

To all whom it may concern:

Be it known that I, WILLIAM H. BRISTOL, a citizen of the United States, and a resident of Waterbury, in the county of New Haven 5 and State of Connecticut, have invented certain new and useful Improvements in Electrical Indicating or Recording Apparatus, of which the following is a specification.

The invention relates to electrical indicating and recording apparatus, more particularly to galvanometers, voltmeters, ammeters or wattmeters for indicating or recording the strength and pressure of an electric current or the work done thereby. The apparatus is of the type in which there is a fixed and a movable member, the latter being adapted to be attracted to or repelled from the former; and the invention has for its object to preserve the accuracy of 15 the apparatus by providing for the movable member a proper mounting. This mounting is so constructed and arranged as to be practically free of expansion and contraction in that it is not within influence of any 20 heat generated in the coils, nor subjected to eddy currents.

The nature of the invention will best be understood when described in connection with the accompanying drawings, in 25 which—

Figure 1 is an elevation of the actuating mechanism of a voltmeter to which the invention has been applied, the casing of said voltmeter being shown in section and a portion 35 of the apparatus removed. Fig. 2 is a similar side view of the actuating mechanism. Fig. 3 is a detail perspective of a knife-blade mounting and attached indicating or recording arm.

Similar characters of reference designate 40 corresponding parts throughout the several views.

Referring to the drawings, 10 designates a suitable casing to which the actuating mechanism is secured, and is provided with binding posts 11 and 12 for outside connection. The actuating mechanism, controlling the movement of an indicating or recording arm 13, consists of a stationary member and 45 a movable member shown respectively as a stationary coil 14 and a movable coil 15 adjacent thereto, and adapted in the present instance to be attracted to the former when both are energized. The windings of the 50 two coils are in series and such as to effect

this mutual attraction. The movable coil 15 is supported by a suitable framing 16, which is shown as extending entirely about both coils, although one-half of the same might be omitted. This frame 16 is attached 60 to the movable coil and is carried at its movable coil end by a flexible spring piece 17. The other end of the frame engages a knife blade 18 mounted in suitable knife edge bearings 19 of a frame piece 20, and which knife blade is adapted to rock in accordance with the movement of coil 15 toward and away from the fixed coil 14. The indicating or recording arm 13 is suitably connected with this knife blade 18, partaking 65 of the motion thereof and which corresponds to the movement of coil 15, the latter being a function of the electric pressure applied to the binding posts 11 and 12. Of course, the coil 15 might be replaced by a 70 magnetic disk which could be attracted by the stationary coil 14. In thus providing a supporting frame for the movable coil 15 about said coils 14 and 15, and transmitting the movement of the latter coil therethrough 75 to the indicating or recording arm 13, instead of through a rod extending centrally through the coils as has been the practice heretofore, expansions and contractions of the movement transmitting member, due to 80 the heat produced in the said coil, as well as those due to the heat produced by eddy currents in the member itself, are entirely obviated. These effects of expansion and contraction of the movement transmitting 85 member have proved a serious drawback to apparatus of this type, employing a multiplying device of the character set forth and which is extremely sensitive and susceptible 90 to very small changes in the relative position of the coils, that is to say the movement of one coil toward and away from another. It has been proposed to employ for this purpose a central rod of insulating material which, of course, would provide 95 against the production of heat through eddy currents; but such rods have not proved satisfactory because of the impossibility of obtaining the material with a practically zero coefficient of expansion, as well as from 100 the fact that the rods warp considerably. In locating the frame, as herein set forth, beyond the influence of the heat generated in the coils, as well as beyond the range of 105 magnetic influence, none of the difficulties 110

aforesaid are encountered and the instrument is extremely accurate.

I claim:—

1. In an electrical measuring instrument, 5 the combination with a stationary member and a movable member within the influence of said stationary member, of a frame supporting said movable member and passing about said stationary member, a suitable support for one end of said frame, a rocking support for the other end of said frame, and an arm connected with said rocking support.

2. In an electrical measuring instrument, 15 the combination with two coils, one of which is movable, of a frame supporting said movable coil and passing about said stationary solenoid, a suitable support for one end of said frame, a rocking support for the other end of said frame, and an arm connected 20 with said rocking support.

3. In an electrical measuring instrument, 25 the combination with a stationary member and a movable member within the influence of said stationary member, of a frame sup- porting said movable member and passing about said stationary member, a rod extending from one end of said frame, means to support said rod, a rod extending from the other end of said frame, a rocking support 30 for the said latter rod, and an arm connected with said rocking support.

4. In an electrical measuring instrument, 35 the combination with a stationary member and a movable member within the influence of said stationary member, of a frame sup- porting said movable member and passing about said stationary member, a rod extending outwardly in the axis of said members from one end of said frame, flexible means to support said rod, a rod extending in- 40 wardly in the axis of said members from the other end of said frame, a rocking support for the said latter rod, and an arm connected with said rocking support.

5. In an electrical measuring instrument, 45 the combination with two coils, one of which is movable, of a frame supporting said movable coil and surrounding both of said coils, a rod extending outwardly in the axis of 50 said coils from one end of said frame, flexi- 55 ble means to support the same, a rod extending inwardly in the axis of said coils from the other end of said frame, a rocking support for said latter rod, and an arm connected with said rocking support.

Signed at New York, in the county of New York, and State of New York, this 28th day of March A. D. 1912.

WILLIAM H. BRISTOL.
